UNITED STATES PATENT OFFICE.

EDWIN E. ROBINSON, OF AKRON, OHIO, ASSIGNOR TO AMERICAN RADIATOR COMPANY, OF CHICAGO, ILLINOIS, A CORPORATION OF NEW JERSEY.

TIRE-LINER CLEANER.

Application filed October 27, 1920. Serial No. 420,067.

To all whom it may concern:

Be it known that I, EDWIN E. ROBINSON, a citizen of the United States, residing at Akron, in the county of Summit and State 5 of Ohio, have invented new and useful Improvements in Tire-Liner Cleaners, of which the following is a full, clear, concise, and exact description, reference being had to the accompanying drawing, forming a part of 10 this specification.

My invention relates to improvements in means for cleaning fabrics and has particular reference to devices adapted to clean what is known in the art as tire liners.

One of the objections to the forms of machines heretofore used for this purpose is that after a certain amount of use the edges of the vacuum nozzles become worn and roughened whereby the fabric, in being 15 drawn over these nozzles is torn or split. As these fabrics are made in long lengths and as the slightest roughness or tear in a length destroys the value of the entire fabric, it is desirable to provide means whereby the danger of tearing the same is obviated.

It is one of the objects of my invention to provide means whereby the wear on the nozzles may be taken care of and a smooth 20 nozzle surface always be provided.

For the purpose of disclosing my invention I have illustrated one embodiment thereof in the accompany drawings in which

Figure 1 is a side elevation of a cleaning 35 apparatus embodying my invention—part of the same being shown in section;

Fig. 2 is a plan view thereof;

Fig. 3 is a sectional view of one of the 40 tubular nozzles showing the wear plate in position;

Fig. 4 is a perspective view of the wear tube or plate;

Fig. 5 is a sectional view of one of the 45 nozzles showing the modified form of wear plate, and

Fig. 6 is a perspective view of one of the modified wear plates.

In the embodiment illustrated, upon a 50 suitable table or bench 1 is mounted a pair of rollers 2 and 3 and these rollers are mounted at opposite ends of the bench and may be removably mounted if desired. The fabric is wound on one roll, the roll 2, and is unwound therefrom on the roll 3, a suitable driving pulley 4 being provided on

the shaft of the roll for operating the roll mechanically.

Extending transversely of the bench and in the path of the fabric as it passes from one roll to the other, is a cleaning apparatus. This apparatus consists, as shown, of a pair of horizontally disposed transversely extending tubes 5 and 6 arranged one in front of the other and one preferably in a lower plane than the other. Each of these 60 tubes is provided with a longitudinally extending slot 7 in the face thereof. The slot in the tube 6 is towards the lower portion of the tube and that in the tube 5 in the upper portion of the tube so that as the fabric is drawn between the tubes, it passes under one tube and then takes a path upwardly and over the other tube. These tubes preferably take the form of pipes and are supported in position by suitable brackets or heads 8 one on each side of the bench. 70

The opposite ends of the tubes are connected with branch pipes 11 each of which is closed at one end by a suitable nipple or nut 12; the opposite end being connected 80 to a communicating pipe 13 by suitable elbows 14. One of the branch pipes 11 is provided with a coupling 15 by which it is connected by means of a pipe 16 with a suitable vacuum producing device 17 preferably driven by an electric motor. 85

In the operation of the device so far described, the fabric is passed beneath one pipe and above the other and due to the connection of the vacuum producing device 90 17 with the two pipes air is drawn through the fabric as it passes over the slots in the pipe removing all dirt and dust from both sides of the fabric, one side of the fabric being cleaned as it passes over the lower pipe and the other side of the fabric being cleaned as it passes over the upper pipe. 95

In commercial use it has been found that the edges of the slots 7 become worn and roughened so that the fabric in passing over these slots is frequently cut and destroyed. In order to obviate this difficulty I provide separate wear plates for the slots which may be made of polished steel or the like, the tubes 5 being generally merely iron pipe, and which may be readily removed from time to time as they wear. 100

In the embodiment illustrated in Figs. 3 and 4, this wear plate takes the form of a split tube 18 which has the edges of the 110

slot 19 thereof turned back upon themselves as at 20. This tubular wear plate may be slipped over the nozzles 6 from the end or may be opened and sprung over the 5 nozzles. The turned back portions 20 fit within the slot 6 and turn back upon the inner face 21 of the slots so that a rounded edge is provided at the slotted opening in the nozzles and at the point over which 10 the fabric passes thus providing a smooth surface over which the fabric may readily slip without danger of being destroyed or cut.

In the form illustrated in Figs. 5 and 6, 15 instead of making the wear plate in the form of a tubular member I make the wear plate in the form of elongated plates 22 having the rounded and turned in portion 20 similar to the portion 20 on the tubular member 18. 20 These wear plates may be secured on the nozzles in any desired manner as by counter sunk screws 23.

Having thus described my invention what I claim as new and desire to secure by 25 Letters Patent is:

1. In a device of the character described, the combination with a tubular member having an elongated slot therein with opposite

angular edges, of removable means secured to said tubular member for guarding said 30 edges, said means including portions extending over and conforming in shape to said member at opposite sides of said slot and rounded edge portions extending inwardly into said slot and embracing said 35 edges to provide curved guards therefor to prevent damage to the material engaged.

2. In a device of the character described, the combination with a tubular member having an elongated slot therein, of a removable longitudinally split sleeve adapted to 40 slidably engage said member and to enclose the same, said sleeve having its longitudinal edges rounded and turned inwardly to embrace the edges of the slot in said tubular member whereby to provide removable, curved wear plates over the edges of said slot.

In witness whereof, I have hereunto subscribed my name in the presence of two 50 witnesses.

EDWIN E. ROBINSON.
